Daniel H. Bond of Canterbury, Connecticut
Letters Patent

9803X

(507)

The Schedule referred to in these Letters Patent, and making part of the same, containing a description in the words of the said Daniel H. Bond himself, of his Improvement in the manufacture of Ladies and Gentlemen's Leather over-shoed.

To all to whom these presents shall come:

Be it known that I, Daniel H. Bond of Canterbury, in the County of Windham and State of Connecticut have invented a new and useful improvement in the making, or manufacturing, of Ladies and Gentlemen's over-shoed of leather which invention is as follows:

The leather should be dressed in the same manner as harness or saddle leather, and from $\frac{1}{2}$ to $\frac{1}{4}$ of an inch in thickness. The shoe contains but one piece of leather, the upper and sole joining between the heel and the ball, there is a seam joining the sole and the upper from the ball to the center of the toe if round, or if the toe is to be made square, the sole is cut about one inch longer than the last, made pointed and turned over the end of the last, so that three seams connecting the sole and the upper will meet at the corner of the toe and meet in a point on the top of the shoe about one inch from each corner, from this point a seam extends about two inches towards the instep on the top of the shoe, at the termination of this seam the leather is cut about one inch and is stitched or bound directly from this stitching, or facing, the upper is left open to the top the leather as before observed being over the instep about one inch and is secured

with a strap and buckle - the quarters at the heel are closed up, similar to the quarters of a common shoe, there is a short seam joining the sole to the quarters around the back part of the heel. The shoe is closed on the wrong sides and turned which is scarcely done dipping it in warm water, it is then lasted while wet and dried on the last a heel may be put to it with pins or nails. When the shoe is perfectly dry, the last is taken out, and an inner sole or lining connected to the bottom on the inside, the shoe may then be made water proof, by Indian Rubber prepared in the following way. Take one gallon of the oil of tar, and put into it about 6 ounces of Indian Rubber cut into small pieces, set it in a warm place and stir it occasionally until the Rubber is dissolved, give the shoe two or three good coats of this bath inside and out and it is perfectly impervious to water. Common resin softened with the above preparation makes a very good cement for the inner sole or lining.

At witness whereof I have sub-
scribed my name the 27th April 1836.

Wm. H. Jones Daniel M. Bond
Rufus D. Hinman
David W. Adams.
